UNITED STATES PATENT OFFICE.

PETER G. VAN WIE, OF DETROIT, MICHIGAN, ASSIGNOR TO THE IDEAL MANUFACTURING COMPANY, OF SAME PLACE.

DESIGN FOR A STOVE.

SPECIFICATION forming part of Design No. 34,419, dated April 23, 1901.

Application filed April 1, 1901. Serial No. 53,989. Term of patent 14 years.

To all whom it may concern:

Be it known that I, PETER G. VAN WIE, a citizen of the United States, residing at Detroit, in the county of Wayne and State of Michigan, have invented and produced a certain new and original Design for a Stove, of which the following is a specification, reference being had therein to the accompanying drawing, in which the stove is shown in perspective.

A is an oblong body having a square base. B is an open-work top of slightly-greater diameter than the body, so as to form an overhanging flange. This top is rounded at the corners and has an imperforate marginal portion *a* extending around the four sides of the square. From the center of each side is an inwardly-extending bar *b*, dividing the top into four squares. Each of these squares has arranged therein a scalloped ring *d*, connected by radial bars to the bars *b* and to the marginal portion *a*.

The front of the body is cut away to form

an open panel immediately below the top B, and below this is arranged a rectangular door C. This door has a swell front substantially in the form of a cylindrical segment having a horizontal axis. Below the door C is arranged a door D, of similar form but of lesser height.

E represents feet of angle-bar cross-section extending downward from the corners of the body and curving outward.

The leading feature of the design is the oblong body having a square base, the open-work top, the swell doors, and the outwardly-curving angle-feet.

What I claim as my invention is—

The design for a stove, substantially as herein shown and described.

In testimony whereof I affix my signature in presence of two witnesses.

PETER G. VAN WIE.
